UNITED STATES PATENT OFFICE.

JOHN BOYD AND THOMAS A. BOYD, OF GLASGOW, COUNTY OF LANARK,
SCOTLAND.

MACHINE FOR WINDING YARN OR THREAD.

SPECIFICATION forming part of Letters Patent No. 276,758, dated May 1, 1883.

Application filed October 20, 1881. (No model.)

To all whom it may concern:

Be it known that we, JOHN BOYD and THOMAS ALEXANDER BOYD, of Glasgow, in the county of Lanark, in the Kingdom of Great Britain and Ireland, have invented a new and useful Improvement in Machines for Winding Yarn or Thread, of which the following is a specification.

Our invention consists of certain improvements in the construction of machines for winding yarn or thread, in which it is desirable to stop the winding action of the machine when there is an excessive strain on the thread from its being entangled or other cause, so that the machine may be stopped before the thread breaks.

Our invention is also applicable to machines for winding, twisting, reeling, and warping yarns, ropes, wires, &c., and to other analogous machines, and by it the action of these machines in whole or in part may be stopped.

The view in the accompanying drawing is a vertical section of a winding and clearing machine embodying our invention, the same devices being shown in duplicate on opposite sides of the machine, so that a description of one set of devices will apply to both. The devices on the left-hand side of the figure are all shown in operative position, while on the right-hand side the bobbin or spool 1, on which the yarn is being wound, is shown as lifted clear of the driving-drum 2 when the winding action is stopped.

The winding devices illustrated in the drawing are similar to those shown in our United States Letters Patent No. 217,769, dated July 22, 1879, and consist of a driving-drum, 2, mounted in bearings in the frame, and supporting on its upper periphery during the winding operation the bobbin 1, which is driven by frictional contact with the drum. This bobbin 1 is carried by the two-armed lever 3, pivoted to the frame and curved on its under side, so that by the movement of the hand-lever 3³ the lever 3 may lift the bobbin out of or lower it into contact with the drum, as set forth in our patent.

The thread or yarn, 4, to be wound onto the bobbin is shown in the drawing as being led from a hank, 5, carried on "racers" or reels 6, supported in brackets 7 on the fixed rails or

beams 8 of the frame of the machine. Instead of being drawn off hanks, the yarns or threads may be led from cops or bobbins, and from the bobbins, cops, or bobbins they pass over rods 9, 55 which may be provided with clearing-fingers 10, adjustable to clear the threads of lumps and imperfections as the threads pass between the fingers. The threads thence pass through traverse-guides 11, carried by the traverse-bar 12, to which an intermittent reciprocating motion is imparted by any of the usual means. The threads, after passing through these guides, pass over rods 13 on pivoted levers 14, carrying the pivoted stopper-slips 17, to be introduced between the driving-drum and bobbin. These stopper-levers are pivoted to the main transverse rail 15, and are provided with adjustable counterbalance weights 16, which can be set by means of screw-shanks so as to properly counterbalance threads or yarns of different strengths. A weak thread requires only a slight counter-weight, while a strong thread may be wound with a much greater counter-weight. Each counter-balance 16 so acts on its lever 14 against the strain on the thread as to keep the said lever under ordinary conditions in contact with the stop-pin 3' on the arm of the bobbin-carrier 3, and the slip 17 held back from being interposed between the 80 bobbin and its driving-drum, as shown at the left-hand side of the figure in the drawing.

In the stop-motion illustrated in our patent above cited the parts were so constructed that on the breaking of a thread the weight of the 85 counter-balance would cause the stopper-slip to enter between the driving-drum and bobbin. In our present machine the action is the opposite of this. The counter-weight tends to pull the slip back from the bobbin, and the slip is caused to enter between the pulley and bobbin only when an undue increase in the tension on the thread 4, arising from the entangling of the thread in the hank or catching of a lump in the clearer 10, or other cause, 95 overcomes the counter-weight 16 and pulls the lever 14 over. The stopper-slip 17 will thus be introduced between the driving-drum and bobbin, which together will pull it forward until the stopper-lever 14 comes in contact with a front stop-pin, 3², on one of the arms of the bobbin-carrier 3, as shown at the right-hand

side of the figure in the drawing. By this introduction of the slip 17 between the driving-drum and bobbin the winding action will be instantly stopped, and the stopper-slip will be held in its forward position by the friction of the driving-drum and the pressure of the bobbin.

As by the construction described the machine is stopped before the thread breaks, it is not necessary for the operator to search for one end on the bobbin and the other on the hank to piece them, as must be the case where the thread breaks. The operator, having removed the obstruction from the entangled hank or thread caught in the clearer or other cause of stoppage, slightly raises the bobbin by means of the arms 3 and lever 3³, so as to allow the stopper-lever 14 and its slip to fall back, and, the bobbin being now again lowered onto the driving-drum, the winding of the thread is resumed.

We claim as our invention—

1. The combination of a driving-drum with a movable lever carrying a stopper-slip, and acted on by the thread or yarn as the latter passes to the bobbin, and provided with a balancing device to counteract the strain of the

thread or yarn, whereby an undue increase of the strain on the latter will overcome the counter-strain on the stopper-lever, and introduce the slip between the bobbin being wound and the drum, which completes the stoppage of the bobbin, all substantially as set forth.

2. The combination of a driving-drum with a movable lever carrying a stopper-slip, and acted on by the thread or yarn as the latter passes to the bobbin, and provided with a balancing device adjustable to counteract the strains of threads of different strengths, substantially as set forth.

3. The combination of a driving-drum with a pivoted lever carrying a stopper-slip, and acted on at one end by the thread or yarn, and provided at the other with an adjustable counterbalancing device, substantially as described.

In testimony whereof we have signed our names to this specification in the presence of two subscribing witnesses.

JOHN BOYD.

THOMAS ALEXANDER BOYD.
